ROLL COATING MACHINE FOR MESSAGE
REGISTER WHEELS

Andrew J. Fedor, Chicago, Ill., assignor to Western Electric Company, Incorporated, New York, N. Y., a corporation of New York

Application August 15, 1951, Serial No. 241,986

5 Claims. (Cl. 118—233)

1
This invention relates to a roll coating machine and more particularly to a machine for rolling a coating composition onto the peripheral surfaces of number wheels.

In counting devices for registering the number of movements of an element, wheels are employed having a series of numerals printed or otherwise indicated thereon. In some types of devices these wheels have cylindrical peripheral surfaces on which is applied a coating composition of one color forming the background color and on which the numbers of a contrasting color are printed. Heretofore, according to one method of marking the wheels, the background coating was applied to the wheels by assembling groups of the wheels on mandrels with the peripheral edges of the wheels in abutting relation so that each group of wheels formed an elongated cylindrical surface on which a coating composition of one color was sprayed. This manner of coating the wheels was satisfactory where the ends or edge portions of the peripheral surfaces of the wheels could be placed in abutting relation to each other to form a continuous cylindrical surface from one to the other of the wheels. However, where the wheels are of a design where the hubs extended axially beyond the edge of the cylindrical peripheral surface so that when a plurality of the wheels are mounted on a mandrel, the edges of the peripheral surfaces of the wheels are spaced apart, the spraying of the first or background coating onto the peripheral surface of the wheels is not satisfactory in that the sprayed coating is not confined to the peripheral cylindrical surface of the wheels, but gets on other exposed surfaces of the wheels, such as the hub portions. This is especially undesirable in that the appearance of the parts thus sprayed renders them unacceptable, and in cases where the wheels are molded with gear teeth formed in the hub or other portions thereof, any coating on the teeth portions of the wheels interferes with the normal operation of the registering mechanism.

It is an object of the present invention to provide a machine for roll coating articles.

In accordance with one embodiment of the invention, there is provided a rotating transfer roller, a supply of a coating composition, mechanism for applying a thin layer of the coating composition onto the transfer roller, a holder having a pair of notched arms for receiving an arbor therein on which a plurality of the wheels to be coated are supported, the holder having a normal position for supporting the arbor and the wheels thereon in spaced relation to the transfer

5 roller and being movable into an operative position to carry the wheels into engagement with the transfer roller, and an actuating member movable from a normally open position to a closed position to hold the arbor in position on the holder and for moving the holder and the arbor with the wheels thereon into an operative position with the periphery of the wheels in engagement with the coating composition on the 10 transfer roller whereby the coating is rolled from the transfer roller onto the peripheral surfaces of the wheels to coat the wheels, after which the holder and the member are returned to their normal positions and the arbor and the coated 15 wheels removed from the machine.

Other objects and advantages of the invention will become apparent by reference to the following detailed description thereof when considered in conjunction with the accompanying drawings 20 illustrating a preferred embodiment thereof, in which

Fig. 1 is a plan view of the machine with parts broken away;

Fig. 2 is a view of the arbor with a plurality 25 of the wheels shown in dotted lines thereon;

Figs. 3 and 4 are side and end views, respectively, of one of the wheels which are to be coated;

Fig. 5 is a vertical longitudinal sectional view 30 of the machine taken on the line 5—5 of Fig. 1, showing the holder in operative position with the wheels to be coated in engagement with the transfer roller;

Fig. 5^a is a fragmentary vertical sectional view 35 showing one of the arms for adjustably supporting a transfer roll and means for adjusting the position of the arm;

Fig. 6 is a fragmentary view of a portion of the 40 device shown in Fig. 5 with the holder in its normal inoperative position;

Fig. 7 is a vertical transverse sectional view taken on the line 7—7 of Fig. 5; and

Fig. 8 is a detailed cross-sectional view taken on the line 8—8 of Fig. 6.

45 Referring now to the drawings, one type of the number wheels 10 which are to be coated is shown in Figs. 3 and 4. Each of the wheels 10 has a cylindrical peripheral surface 11, on which a thin coating of composition of one color is to be applied to form the background color on which the numbers of a contrasting color subsequently are to be applied. The wheel 10 has a central bore 12 passing through hub portions 13 thereon, one of which is formed in the shape of a gear 14, and on one end face of the wheel near the periph-

ery thereof is molded a pair of teeth 15. A plurality of the wheels are adapted to be assembled on a rod or arbor 18 (Figs. 2 and 7) having a collar or shoulder 19 thereon in spaced relation to and adjacent one end of the rod, as shown in Fig. 2.

The arbor 18, with the wheels 10 assembled thereon, is adapted to be positioned in a holder 22 (Figs. 5 and 6) of the coating machine with the end portions of the arbor 18 fitting in notches 23 formed in a pair of arms 24 of the holder. The arms 24, which are spaced apart a predetermined distance, are secured to or formed integral with a sleeve 26 (Fig. 8) which is mounted for oscillatable movement on a shaft 27. The shaft 27 is supported in a pair of bearing bushings 28 and 29, which are mounted in vertical plates or walls 30 and 31, respectively, which, in turn, are mounted on the base 32 of the machine. The bearing bushings 28 and 29 serve to lock the holder 22 against axial movement on the shaft 27. A coiled spring 35 on the bushing 28 has one end thereof anchored in the wall 30 and the other end secured to the arm 24 to stress the holder for rotation in a clockwise direction and yieldably maintain it in an upper inoperative position, as shown in Fig. 6, against a stop member 38 on the wall 30. The holder 22 supports the arbor 18 and the wheels 10 thereon in a normal inoperative position (Fig. 6) above an applicator or transfer roller 40 and parallel to the axis thereof and is movable downwardly into an operative position (Fig. 5) to carry the wheels 10 into close proximity and in substantial engagement with the periphery of the roller 40.

An actuating member or lever 42 is provided for clamping the arbor onto the holder 22 and for moving the holder and the arbor 18 with the wheels 10 thereon from the inoperative to the operative position. The member 42 comprises a pair of arms 43—43 secured to a block 45, which is mounted for oscillatable movement on the sleeve 26 between the arms 24 of the holder 22. The forward portions of the arms 43 are connected together by a bail-shaped handle member 47 and are adapted to engage the shoulder portion 19 and a portion of the arbor 18 when the actuating member is moved from an open position as shown in Fig. 6 to a closed position to grip the arbor in the notches 23 in the arms 24 of the holder 22. After the actuator member 42 has been moved into engagement with the arbor 18, continued movement of the member will carry the holder and the arbor with the wheels 10 thereon into the operative position shown in Fig. 5. An adjustable stop screw 49, mounted on one of the arms 24, is engageable with a sleeve 50 on a shaft 51, on which the transfer roll 40 is mounted, to stop the downward movement of the holder and accurately position the wheels 10 relative to the periphery of the roller 40 during the roll-coating operating. A spring 53 stresses the actuating member 42 in a clockwise direction and serves to return it to its normal open position, shown in Fig. 6, in which position the actuating member is stopped by the engagement of a pin 54 on the block 45 with an arm 24 of the holder 22.

The shaft 51, on which the transfer roll 40 is rotatably mounted, is fixed to and supported in one end of a pair of arms 51, which are secured at their other ends to a shaft 58 journaled for oscillating movement in the walls 30 and 31. As shown in Fig. 7, the shaft 51 extends through clearance slots or apertures in the walls 30 and 31.

31 and has a nob or handle portion 59, by means of which the roller may be manually rotated and vertically moved to facilitate the cleaning thereof. A pair of springs 60, connected to the arms 57, urge the roller 40 downwardly and an extension 61 (Fig. 5a) on one of the arms 57 is engageable with a set screw 62 (Figs. 1 and 5a) adjustably mounted in a lug 63 on the wall 31, whereby the roller 40 is accurately positioned relative to a vibrator roller 65 to regulate the degree of pressure between the rollers 40 and 65.

The coating of composition applied to the wheels 10 from the transfer roller 40 is carried to the roller 40 through a series of rollers including the vibrator roll 65, distributor roll 68, vibrator roll 69, distributor rolls 70 and 71, ductor roll 72, and a supply roll 73 from a supply 74 of the composition in a container or fountain 75. The vibrator roll 65 is fixed to a shaft 80 (Fig. 7), 15 which is rotatably and slidably mounted in bearing apertures in the plates 30 and 31 and has a pair of gears 81 and 82 fixed thereto, the former of which meshes with a gear 83 fixed to a drive shaft 84. The drive shaft 84 may be driven by any suitable means, such as a speed reducing unit 85, which, in turn, is driven from an electric motor (not shown) mounted on the base 32. The shaft 80 has a barrel cam 87 fixed thereto, in the cam groove of which rides a stationary cam follower 88 formed on a bracket 89 fixed to the side wall 31 of the machine for imparting axial reciprocation to the vibrator roller 65 as it rotates.

The gear 82 on the shaft 81 meshes with an idler gear 92 suitably mounted for rotation on the side wall 30, and the gear 92, in turn, meshes with a gear 94 fixed to a shaft 95, on which the distributor roller 71 is fixed. The distributor rollers 68 and 70 are formed on shafts 96 and 97, respectively, which are rotatably mounted in bearing blocks 98 and 99 removably mounted in slots 100 and 101 in the walls 30 and 31. The rollers 68 and 70 bear against the rollers 65 and 71, respectively, and support the vibrator roll 69. The vibrator roll 69 is rotatably mounted on a shaft 105, which, at its ends, is fixed to posts 106, and the posts 106 are slidably mounted in slots 107 in the side walls 30 and 31 of the machine for holding the vibrator roll 69 against axial and lateral displacement as it rests on the distributor rolls 68 and 70. A suitable mechanism (not shown) is contained within the vibrator roll 69 to impart a predetermined axial reciprocatory movement thereto in response to rotation thereof.

55 The ductor roll 72 is supported for rotation in the ends of a pair of arms 110 fixed to a shaft 111, which is mounted for rocking movement in bearing apertures in the side plates 30 and 31 and is adapted to be oscillated to and from engagement with the distributor roll 71 and the supply roll 73. A spring 112 connected to one of the arms 110 stresses the arms for movement in a clockwise direction and an arm 114 fixed to the shaft 111 has a cam follower 115 thereon engaging the periphery of the cam 116 fixed to a shaft 117. Journaled in bearing apertures in the plates 30 and 31, the shaft 117 has a gear 118 fixed thereto which meshes with and is driven from the gear 34. The supply roller 73 is adapted to be rotated step by step and is mounted on a shaft 125, which is journaled in suitable bearings in the walls 30 and 31 and has a ratchet 126 fixed thereto which is adapted to be driven by a pawl 127 pivotally mounted on an oscillatable arm 128. The arm 128 is connected to one end of a link

129, the other end of which is pivotally connected to the gear 118 in eccentric relation to the axis of the shaft 117 so that, as the gear 118 rotates, it acts as a crank to impart oscillation to the arm 128 and pawl 127 to impart step by step rotation to the ink roller 73. Rotated from a positive gear drive, the rollers 65 and 71 impart rotation to the transfer roller 40 and the distributor rollers 68 and 70 in engagement therewith, and the vibrator roll 69 is rotated through engagement with the distributor rolls 68 and 70.

A thin film of the ink or coating composition, governed by the setting of a doctor blade 132, adheres to the supply roller 73 as it is advanced step by step, and the ductor rollers 72 serve to transfer the composition from the roller 73 onto the roller 71. The coating composition is then rolled into a thin smooth film and is transferred from one roller to another until it arrives at the roller 40 and is applied thereon in a thin even film.

In the operation of the device, sets of wheels 10 are assembled on arbors 18 and a supply of the arbors with the wheels assembled thereon is stationed close to the machine. The operator takes the arbors in succession and lays each one with the ends thereof in the grooves 23 of the arms 24 of the holder (Fig. 6), after which he presses the handle portion 47 of the actuator member 42 downwardly, causing the arms 43 to first engage the arbor and lock it in position in the holder 24 and then move the holder and the mandrel with the wheels thereon into the operative position shown in Fig. 5, where the periphery of the wheels 10 engage the film of composition on the transfer roller 40. The holder 24 may be held down with the wheels 10 in engagement with the roller 40 for several rotations of the wheels to cause a film of coating material to be rolled onto and adhere to the peripheral surface of the wheels. The operator then releases the downward pressure of the actuator member 42, permitting the holder to return to its inoperative position and the actuator member 42 to return to its open position, as shown in Fig. 6, after which the arbor 18, with the coated wheels 10 thereon, is removed from the machine and placed in a rack.

It is to be understood that the above-described arrangements are simply illustrative of the application of the principles of the invention. Numerous other arrangements may be readily devised by those skilled in the art which will embody the principles of the invention and fall within the spirit and scope thereof.

What is claimed is:

1. A roll coating machine for coating the peripheries of a plurality of wheels mounted on an arbor comprising a transfer roller mounted for rotation about a fixed axis, means for rotating and applying a coating of composition onto said roller, a holder including a pair of arms engageable with the ends of said arbor for supporting said arbor and the wheels thereon for movement to and from an inoperative position in spaced relation to said transfer roller and an operative position in which said wheels are in engagement with said roller, resilient means for moving said arms to said inoperative position, an actuating member having a pair of arms movable from a normal position spaced from an arbor in said holder into engagement with an arbor in said holder to grip said arbor and to move said holder into operative position, and resilient means for moving said actuating member into said normal position.

2. A roll coating machine for applying a coating composition onto the peripheries of a plurality of wheels supported on an arbor comprising a transfer roller mounted for rotation about a fixed axis, a receptacle for a supply of said composition, means for distributing a thin layer of said composition onto said transfer roller, a holder having seats engageable with the ends of said arbor for supporting the arbor and the wheels thereon, means mounting said holder and an arbor with the wheels thereon for movement to and from an inoperative position in spaced relation to said applicator and an operative position in which the wheels are in engagement with said applicator roller, yieldable means for retaining said holder in said inoperative position, an actuator member, means mounting said actuator member for movement from a normal position into engagement with an arbor in said holder to grip the arbor in said holder and to move said holder and the arbor with the wheels thereon to said operative position, and yieldable means for retaining said actuator member in said normal position.

3. A roll coating machine for coating the periphery of a plurality of wheels mounted on an arbor comprising a transfer roller, means for rotating and applying a coating of composition onto said roller, a holder having a pair of arms with seats for receiving the arbor therein to support said arbor and the wheels, means mounting said holder for movement to guide said arbor and the wheels thereon toward and away from said roller and in parallel relation thereto whereby said wheels may be pressed into engagement with said roller, stop means for arresting the movement of said holder in one direction to limit the pressure of said wheels against said roller, and means for adjusting said stop means to vary the pressure between said wheels and said roller.

4. A roll coating machine for coating the periphery of a plurality of wheels mounted on an arbor comprising a transfer roller, means for rotating and applying a coating of composition onto said roller, a holder having a pair of arms with seats for receiving the arbor therein to support said arbor and the wheels, means mounting said holder for movement to guide said arbor and the wheels thereon toward and away from said roller and in parallel relation thereto whereby said wheels may be pressed into engagement with said roller, stop means for arresting the movement of said holder in one direction to limit the pressure of said wheels against said roller, means for adjusting said stop means to vary the pressure between said wheels and said roller, and means for yieldably retaining said holder with the arms in a normal position for receiving and supporting an arbor with said wheels thereon in spaced relation to said roller.

5. A roll coating machine for coating the peripheries of a plurality of wheels mounted on an arbor comprising a transfer roller, means for rotating and applying a coating of composition onto said roller, a holder having a pair of arms with seats for receiving the arbor therein to support said arbor and the wheels thereon, means pivotally mounting said holder for movement about a predetermined axis to guide said arbor and the wheels thereon to and from said roller and in parallel relation thereto whereby said wheels may be guided and pressed into engagement with said roller, stop means for stopping the movement of said holder toward said roller in a predetermined position to control the pres-

sure between said wheels and said roller, means for yieldably retaining said holder and an arbor and wheels therein in a normal position in spaced relation to said roller, an actuating member, means mounting said actuating member for pivotal movement about said predetermined axis into engagement with said holder and the arbor therein to hold said arbor on said holder and to move said holder against said stop means to effect the engagement of said wheels with said 10 roller, and means for yieldably holding said actuating member in a normal position in spaced relation to the seats on said arms of the holder

to permit the loading and unloading of an arbor with wheels thereon into said holder.
